CLOTH CUTTING MACHINE

William Bangser, New York, N. Y., assignor to H. Maimin Company, Incorporated, a corporation of New York

Application January 14, 1931. Serial No. 508,683

14 Claims. (Cl. 164—75)

This invention relates to cloth-cutting machines of the reciprocating knife type and has for its object the provision of means for oscillating the reciprocating knife during the cutting operation so that the cloth is cut with a pinked or scalloped edge.

Portable cloth-cutting machines of the reciprocating knife type comprise generally a base carrying a vertical standard in which the knife is mounted and which is surmounted by a motor for reciprocating the knife. The knife is provided with a sharpened vertical edge and a sharpened lower edge, the latter cooperating with a slotted throat plate in the base of the machine to shear the cloth in the lower part of the lay. There is also a bifurcated presser foot overlying the cloth lay and extending on either side of the knife, its function being to hold the cloth in position and prevent upward movement which might otherwise be occasioned by the reciprocation of the knife. The base plate is provided with rollers which enable the operator to move the machine over the work table by means of a handle fixed to and extending rearwardly from the upper end of the standard.

It is well recognized that for most efficient cutting the motor, knife, knife guide, presser foot and throat plate must be nicely adjusted with relation to one another. In accordance with the present invention, therefore, means are provided for oscillating the knife about its vertical axis without disturbing this relationship. This is accomplished by constructing the motor, the knife guide, with its reciprocating knife, the throat plate and presser foot as a unit and mounting this unit for oscillation on the relatively fixed base plate and standard. Thus the relationship existing among the motor with its reciprocating cross-head, the knife, the knife guide, the slotted throat plate and the presser foot remains unchanged during the cutting operation, although with reference to the standard and base plate and to the cloth, the knife is oscillating.

The form of the pinked or scalloped edge produced by a machine of this type depends upon two factors—the period of oscillation of the knife and the rate of movement of the machine relative to the cloth. Thus, for a given period of oscillation the number of scallops per inch will depend directly upon the rate at which the operator moves his machine, and as this rate is never uniform, the character of the pinking itself will not be uniform. According to the present invention means are provided for varying the period of oscillation with respect to the rate of movement of the machine relative to the cloth. I do this preferably by oscillating the knife by means of the rollers which support the machine, the period of oscillation thus varying directly with the speed of the machine.

A better understanding of the invention will be obtained from the detail description of certain preferred embodiments which follows, reference being had to the annexed sheet of drawing in which:

Fig. 1 is a side elevation, in part sectional, of the cloth cutting machine of the invention;

Fig. 2 is a cross-sectional view on the line 2—2 of Fig. 1 through the base of the machine;

Fig. 3 is an enlarged cross-sectional view on the line 3—3 of Fig. 1, showing the position occupied by the presser foot relative to the knife;

Fig. 4 is a cross-sectional view on the line 4—4 of Fig. 5;

Fig. 5 is an enlarged cross-sectional view of the connection between the upper end of the knife guide and the motor chassis shown in Fig. 1;

Fig. 6 illustrates the undulating line of cut designed to be made by the cloth cutting machine of the invention.

Corresponding in general with cloth cutting machines of usual design the machine of the present embodiment comprises a flat base plate 1, adapted to roll upon a work table, a standard 2 rising vertically from the base, and a motor chassis 3, including an electric motor 4, located above the upper end of the standard 2. The base plate 1 is of generally oval contour and is dished on its under surface to provide a shell-like housing for two pairs of rollers 6 and 7. The treads of these rollers are of live rubber (or other suitable composition) so as to afford good friction contact with the surface of the work table over which the machine is adapted to be displaced.

The pair of rollers 6 is fixedly mounted upon a shaft 8 near the rear, or trailing, end of the base, this shaft extending transversely between the side walls forming the concave bottom of the base and being journaled in bearing lugs 9 projecting from the walls. The base plate 1, at a point slightly displaced from its geometrical center is provided with a circular opening 10 and this opening is surrounded with a downwardly directed neck 11 extending into the concavity of the bottom of the base plate. Shafts 12, upon each of which is mounted a roller 7, are disposed in alignment with each other and in parallelism with shaft 8 upon the under surface of the base at a position forwardly of the latter shaft. Each of the shafts 12 has one end journaled in a bearing 13 formed on the marginal portion of the shell and its other end received within a bearing 14 on the outer circumference of the neck.

The lower end of the neck upon its inner circumference is screw threaded and threadedly fastened within this portion is a disk 15. Rigidly attached to this disk and rising vertically therefrom at a point located slightly to the rear of its center is the standard 2. The standard is of elongated cross-sectional dimensions and, in a

direction transverse of the base, is of comparatively small thickness. The front edge of the standard for a substantial portion of its length is provided with an arcuate groove 16 (Fig. 3) defining in effect a socket in which is received a knife guide 17. The knife guide comprises a vertically extending rod having a convex rear wall 18 snugly seating within the groove 16 of the standard, the arrangement being such that the 10 knife guide is capable of turning about its longitudinal axis within the groove. The convex wall 18 merges with two side walls 16a and 16b which converge toward the front of the knife guide. For maintaining the knife guide in assembly with the standard 2 the lower end of the guide is provided with a generally circular throat plate 20 snugly received within the opening 10 and supported upon the disk 15 through a ball bearing 21. In order to permit rotation of the throat plate 20 within the opening 10, this plate is provided with an arcuate slot 22 (Fig. 2) furnishing a clearance opening for the standard 2 in different angular positions of the plate.

The knife guide has a slot 23 intersecting the apex defined by the intersection of the two converging walls 16a and 16b, this slot extending throughout the major portion of its length and terminating at its lower end in a recess 24 formed in the throat plate 20. A flat knife 25 having a longitudinal cutting edge 25a slides within the slot 23 of the knife guide 16, the lower end of the knife being inclined and formed with a shearing edge 25b which fits the recess 24 and defines with its slightly sloping edges 26 a throat for severing the bottommost layers of the pile of fabrics. By reason of the construction just described the throat plate 20, oscillating in unison with the knife guide 17 always presents the recess 24 in operative position for receiving the lower shearing edge 25b of the knife. The upper end of the knife is offset as at 27 and is provided with a terminal slot 28 arranged to receive a threaded pin 29 for clamping it to a crosshead 30 by means of a nut, not shown, threaded upon one end of the pin.

The motor chassis 3 comprises a casting 32 providing a rigid support for the motor and a slideway 33 for the crosshead 30, and constituting a frame to which suitable face plates 34 may be attached for housing the moving parts. The armature shaft of the electric motor 4, mounted upon the chassis 3, is provided with a balance crank 35 which is operatively connected to a pin 36 extending laterally from the crosshead 30, located below the crank by means of a connecting rod 37. Consequently as the crank 35 is rotated the crosshead 30 will reciprocate within the slideway 33 carrying with it the knife 25. Since any of the conventional mechanisms for reciprocating the knife of cloth cutting machines may be employed the above mechanism is merely suggestive and requires no further description. A switch 4a may be provided for turning on and off the current for the motor 4.

The upper end of the knife guide 17 terminates in a block 40 (Fig. 5) and this block is provided with a cylindrical recess 41 in axial alignment with the slotted portion of the knife guide but terminating short of the bottom of the block. The lower face of the block at its rear edge is cut away to define a groove 42 and an overhanging ledge 43. The bottom of the recess 41 opens laterally into the vertical wall of the groove through a flared channel 44 as shown in Fig. 4. The block 40 is maintained in rigid assembly

with the motor chassis 3 by means of bolts 45 which are threaded through vertical openings in the ledge 43 and fastened to the bottom of casting 32. It will be evident from the construction just described that oscillation of the knife guide 17 will impart unitary turning movement to the knife blade 25, the throat plate 20 and the motor chassis 3.

The upper end of the standard 2 has formed thereon a flat offset portion 46 extending through the flared channel 44 and clearing the bottom of the recess 41. A stem 47 of generally cylindrical shape but having an intermediate squared portion 47' is integrally joined to the offset portion 46 and projects axially up through the opening 41 to a position above the block 40. The top of the stem is screw threaded to receive a nut 48. A handle bar 49 extending horizontally to the rear of the machine fits, at its inner end, over the squared portion 47' of the stem on which it is retained by the nut 48 so that in the operation of the machine during the oscillation of the block 40, the handle bar remains stationary with the standard. The end of the handle bar is provided with a grip 50 arranged to be grasped by the operator to move the machine over the table. In order to offset the tendency of the knife to lift the chassis 3 lengthwise of the stem 47 upon its upstroke, a thrust-bearing is interposed between the block 40 and the handle bar 49, this bearing consisting of a ball race ring 51 surrounding the stem and contained within a pocket 52 defined by complementary recesses formed in the upper face of the block 40 and the lower face of the handle bar 49. Since the opening 41 in the block 40 is made slightly oversize to facilitate the assembly of the standard 2 with the block 40, the ball race ring 51 serves the additional function of centralizing the stem within the opening. The handle bar is provided with 110 arcuate clearance slots 53 so as not to interfere with the swinging movement of the bolts 45, while the flared channel 44 is of such shape as to permit oscillation of the block.

A presser foot 55 is bifurcated so as to receive 120 with a minimum amount of clearance the cutting edge of the knife. The presser foot resiliently bears against the cloth in front of and upon the two sides of the knife maintaining the fabric in a flat condition and, upon the upstroke 125 of the knife, stripping the topmost layers therefrom. The presser foot is rigidly connected to the lower end of a vertically extending rod 55a fastened at its upper end to the motor chassis and consequently it swings with the chassis.

In order to automatically impart oscillating movement to the knife guide and, consequently, to the motor chassis 3, this embodiment of the invention contemplates the provision of a pair of cams 56 eccentrically displaced 180 degrees upon 135 the shaft 8 carrying the rollers 6 in the base of the machine. Each one of a pair of parallel thrust rods 57 intermediately supported and slidably received within openings formed in a lug 58 on the bottom surface of the base plate 1 has one end in rubbing contact with one of the cams 56 and its opposite end extending through an opening in the neck 11 and bearing against a flat 145 plate 20. These points of contact of the thrust rods 57 with the throat plate 20 are located equidistantly from and upon opposite sides of the center of the throat plate. When, therefore, the shaft 8 revolves, the cams 56 acting against the 150

ends of the thrust rods 57 alternately rock the throat plate back and forth.

In operation, the machine will be supported upon the work table upon which reposes the lay of fabrics to be cut, the uppermost layer having previously been marked in accordance with a predetermined pattern. The motor 4 having been set in operation by means of the switch 4a to reciprocate the knife 25, the operator next grasps the grip 50 and guides the machine over the table advancing the knife through the lay, along the guide lines marked on the top layer of cloth. As the machine rolls over the table upon the rollers 6 and 7, the shaft 8, carrying the rollers 6, is rotated, and, through the eccentrically disposed cams 56 and thrust rods 57, automatically imparts oscillating motion to the throat plate 20, the knife guide 17, the knife 25, and the motor chassis 3. Since the presser foot 55 embracing the knife 25 depends from a portion of the motor chassis, it follows the oscillations of the knife and does not interfere with its angular movement; and the throat plate, moving in unison with the knife, always presents the recess 24 in operative position with respect to the lower shearing edge of the knife. As the period of oscillation is determined by the rate at which the rollers 6 rotate, and as this rotation varies directly with the rate at which the operator moves the machine forward over the work table, the number of scallops per inch and their curvature are fixed and independent of the rate of movement of the machine; whether fast or slow, constant or varying.

35 I claim:

1. In a cloth-cutting machine, a knife and means for automatically oscillating the knife about a vertical axis, said machine being constructed and arranged for bodily displacement relative to the work, the period of oscillation varying with the relative movement of the cloth and the machine.

40 2. In a cloth-cutting machine of the reciprocating knife type, a base plate constructed and arranged for bodily displacement relative to the work, a knife and slotted throat plate mounted on the base plate, and means for automatically oscillating them as a unit about a vertical axis with reference to the base plate in response to movement of the machine.

45 3. In a cloth-cutting machine of the reciprocating knife type, a base plate constructed and arranged for bodily displacement relative to the work, a knife, a motor and slotted-throat plate mounted on the base plate, and means for automatically oscillating them as a unit about a vertical axis with reference to the base plate in response to movement of the machine.

50 4. In a cloth-cutting machine of the reciprocating knife type, a base plate constructed and arranged for bodily displacement relative to the work, a knife, a slotted throat plate and a presser foot mounted on the base plate, and means for automatically oscillating them as a unit about a vertical axis with reference to the base plate in response to movement of the machine.

55 5. In a cloth-cutting machine of the reciprocating knife type, a base plate constructed and arranged for bodily displacement relative to the work, a knife guide, knife and slotted throat plate mounted on the base plate, and means for automatically oscillating them as a unit about a vertical axis with reference to the base plate in response to movement of the machine.

60 6. In a portable cloth-cutting machine of the

reciprocating knife type, rollers for supporting the machine on a work table, and means actuated by the rollers for oscillating the knife about a vertical axis as the machine moves over the table.

65 7. In a portable cloth-cutting machine of the reciprocating knife type, a vertical standard constructed and arranged for displacement relative to the work, a knife guide oscillatable about said standard, a knife reciprocable within the knife guide, means for reciprocating the knife and means for automatically oscillating the knife guide in response to movement of the machine.

70 8. In a cloth-cutting machine of the reciprocating knife type, a base plate, a motor, knife guide, knife, slotted throat plate and presser foot mounted on the base plate, and means for oscillating them as a unit about a vertical axis with reference to the base plate, the period of oscillation varying with the relative movement of the cloth and the machine.

75 9. In a portable cloth-cutting machine of the reciprocating knife type, a base plate, rollers on the base plate for supporting the machine on a work table, a motor, knife guide, slotted throat plate, and presser foot mounted on the base plate, and means actuated by the rollers for oscillating them as a unit about a vertical axis with reference to the base plate as the machine moves over the table.

80 10. In a portable cloth-cutting machine of the reciprocating knife type, a vertical standard constructed and arranged for displacement relative to the work, a knife guide oscillatable about said standard, a knife reciprocable within the knife guide, means for reciprocating the knife, a presser foot arranged in advance of the knife for engaging the work, and means responsive to the displacement of the machine for automatically oscillating the knife guide, knife and presser foot as a unit.

85 11. In a portable cloth-cutting machine of the reciprocating knife type, a vertical standard, a knife guide oscillatable about said standard, a knife reciprocable within the knife guide, means for reciprocating the knife, a handle for displacing the machine upon a work table, and means controlled by the displacement of the machine for oscillating the knife guide.

90 12. In a portable cloth-cutting machine of the reciprocating knife type, a vertical standard, a knife guide oscillatable about said standard, a knife reciprocable within the knife guide, means for reciprocating the knife, a handle for displacing the machine upon a work table, and a roller in frictional contact with the work table for oscillating the knife guide in response to movement of the machine.

95 13. In a portable cloth-cutting machine of the reciprocating knife type, a vertical standard, a knife guide oscillatable about said standard, a knife reciprocable within the knife guide, means for reciprocating the knife, a handle for displacing the machine upon a work table, a roller in frictional contact with the work table, a cam shaft rotatable by the roller, and means connecting the cam shaft and knife guide for oscillating the knife guide in response to the displacement of the machine.

100 14. In a portable cloth-cutting machine, a knife mounted for oscillation about a vertical axis, a roller for supporting the machine upon a work table, and mechanism operated by the roller for oscillating the knife.
